DISPENSER HAVING STEP-BY-STEP ROTATING VALVE WITH MEANS TO PREVENT REVERSE ROTATION THEREOF

Frank K. Wydra, Chicago, Ill.

Application March 26, 1946, Serial No. 657,207

1 Claim. (Cl. 222—248)

1

My invention relates to improvements in measuring and dispensing devices, for use especially, although not necessarily, as a household appliance for measuring and dispensing from jars, and the like.

The primary object of the invention is to provide a simply constructed, inexpensive device for attachment to a wall, or shelf, and to which a screw-threaded jar of granulated coffee, or other comminuted material, may be attached in inverted position to discharge therein, the device being adapted for easy repeat operation to dispense such material in uniformly measured quantities without clogging of the material either in the device or in the jar and without admitting air into the jar, whereby the material in the jar will not deteriorate from exposure to atmospheric air.

To the accomplishment of the above, and subordinate objects presently appearing, a preferred embodiment of my invention has been illustrated in the accompanying drawings, set forth in detail in the succeeding description, and defined in the claim appended hereto.

In said drawings:

Figure 1 is a view in side elevation of my improved measuring and dispensing device in the preferred embodiment thereof,

Figure 2 is a view in vertical section taken on the line 2—2 of Figure 1,

Figure 3 is a fragmentary view in front elevation,

Figure 4 is a view in plan with the auxiliary rotor section removed,

Figure 5 is a view in transverse section taken on the line 5—5 of Figure 2,

Figure 6 is a view in side elevation of the sections of the rotor detached,

Figure 7 is a view in perspective of the rotor operating member,

Figure 8 is a view in plan of the reverse rotation detent, and

Figure 9 is a view in plan of the cover plate.

Referring to the drawings by numerals, according to my invention, as illustrated, a cylindrical, cup-like receptacle 1 is provided, of any suitable light, strong material, such as aluminum, and which embodies an enlarged rim cuff section 2 threaded for screwing onto the threaded neck 3 of a material supplying jar 4, especially one for containing ground coffee. Preferably the cuff section 2 is threaded for application to the well-known "Mason" jar of commerce. The receptacle 1 is provided on one side thereof, constituting its rear side, with a hook-like lateral arm 5 for insertion downwardly into a suitable wall

2

bracket 6 whereby the receptacle 1 with an inverted jar 4 upstanding therefrom may be attached to such a base, as a wall, or shelf, to form either a permanent or removable fixture. The bottom 7 of the receptacle 1 has formed therein a substantially quadrant-shaped discharge opening 8, best shown in Figure 5, and which is arranged at the front of the receptacle, which is to say diametrically opposite the arm 5.

10 The main section 9 of a rotor is fitted in the receptacle 1 and which comprises impeller blades 10 radiating from the axis of said section in ninety degree angular relation. The rotor section 9 fits in the receptacle 1 below the cuff section 2 and rests on the bottom 7 of said receptacle, with its upper end spaced slightly below said cuff section. A short axial bottom stud 11 on said section 9 rotatably fitting in an axial aperture 12 in the bottom 7 of said receptacle 1 centers said section 9 in said receptacle at the bottom thereof.

15 A cover plate 13 surmounts the rotor section 9 and fits in the cuff section 2 on a circumferential ledge 14 formed at the juncture of the cuff section 2 with the remainder of the receptacle 1.

20 The cover plate 13 is provided with an arcuate edge 15 and spaced radial edges 16, 17 arranged in substantially 135° angular relation to form a feed opening 18 in said plate at the side of the receptacle 1 substantially opposite the discharge opening 8 in the bottom 7. Shoulders 19, 20 on said ledge 14, against which the edges 16, 17 of the cover plate 13 are fitted, prevent said cover plate from turning in the cuff section 2. A top stud 21 on the rotor section 9, similar to stud 11, is rotatably fitted in an aperture 22 in said cover plate 13 and centers the rotor section 9 in the receptacle 1 at the top thereof.

25 A rotor operating member 23, in the form of a split, resilient, flat metal ring, with overlapping ends, is rotatably mounted in an internal, circumferential groove 24 formed in the receptacle 1 immediately below the ledge 14. The rotor operating member 23 is retained in the circumferential groove 24 by the cover plate 13 and the rotor section 9, which it surrounds. A hand-grip stud 25 extends laterally from the outermost end of the rotor operating member 23, out of a circumferential, arcuate slot 26 formed in the front of the receptacle 1, and whereby said member is rotatable back and forth, forwardly and rearwardly, respectively. The ends of the slot 26 limit forward and rearward movement of the rotor operating member 23 by engagement with the hand-grip stud 25, and the extent of movement of said member 23 is limited to an arc of substantially

90°. The innermost end of the rotor operating member 23 forms a resilient, ratchet tongue 27 adapted to engage one side of the impeller blades 10, successively, and rotate the rotor section 9 counter-clockwise, as viewed in Figure 4, step by step upon repeated movement of said member forwardly, said tongue 27 being adapted to ratchet over the side edges of said blades 10 when said member 23 is moved rearwardly, and snapping behind said impeller blades 10, successively.

A washer-like, reverse rotation plate 28 is circumposed on the stud 21 and rests on the upper end of the rotor section 9 between said end and the cover plate 13. The reverse rotation plate 28 is provided with a pair of circumferential, resilient, hooked tongues 29, 29' engaging the edges 16, 17 of the cover plate 13, whereby said plate is prevented from turning about the stud 21. A third circumferential, resilient tongue 30 on said plate 28 is adapted to wipingly engage the upper edges of the impeller blades 10 and to snap downwardly behind said blades and thereby block reverse rotation of the rotor section 9 when the rotor operating member 23 is moved rearwardly.

An auxiliary rotor section 31, shorter than the rotor section 9, but otherwise a duplicate thereof, with the exception presently noted, surmounts the cover plate 13 and is adapted to extend into the neck 3 of the jar 4 to act as an agitator. The auxiliary rotor section 31 is detachably attached to the rotor section 9 with its blades 32 vertically aligned with the impeller blades 10. For this purpose, said section 31 is provided with an axial socket 33 threaded onto a stem 34 arising axially from the stud 21. As will be understood, the blades 32 of the auxiliary rotor section 31 clear the cover plate 13 sufficiently for working purposes.

As will now be apparent, the impeller blades 10 of the rotor section 9 are adapted to form in conjunction with the closed bottom, measuring pockets in the receptacle 4, which, when the rotor operating member 23 is rotated repeatedly from its rearward limit of movement, counter-clockwise, into its forward limit, as shown in Figure 4, will be registered successively with the discharge opening 8 so that said pockets will discharge out of said opening 8 successively. As will also be clear, in either limit of movement of the rotor operating member 23, one of said pockets registers with the discharge opening 8, and the others are positioned for feeding of material into the same through the feed opening 18, one of said other pockets being fully registered with said

opening 18 and the others being partially registered therewith. Thus, in either limit of movement of the rotor operating member 23, and during rotation of the rotor section 9 between its limits of movement, said pockets will be fed so that a completely filled pocket is always provided for rotation to the discharge opening 8. The edge 17 of the cover plate 13 levels off the pockets as the same approach the discharge opening 8. The auxiliary rotor section 31 agitates the material in the neck 3 of the jar 4 to provide for free discharge out of said neck and to prevent clogging above the rotor section 9.

The foregoing will, it is believed, suffice to impart a clear understanding of my invention, without further explanation.

Manifestly, the invention, as described, is susceptible of modification without departing from the inventive concept, and right is herein reserved to such modifications as fall within the scope of the appended claim.

What I claim is:

In a measuring and dispensing device of the type including a receptacle having a cover plate 23 with a feed opening therein, a bladed rotor adapted to fit in the receptacle and be rotated in one direction therein, said rotor having a stem journaled in said cover plate, and an apertured reverse rotation plate fitted around said stem between said cover plate and rotor with tongues thereon engaging the edge of said cover plate at said opening to anchor the reverse rotation plate to said cover plate, said reverse rotation plate having a depending resilient ratchet tongue for wipingly engaging the blades of the rotor and flexing downwardly between the same to block reverse rotation of the rotor.
